UNITED STATES PATENT OFFICE.

JAMES T. MURPHY, OF CHICAGO, ILLINOIS.

REFINING ENGINE FOR PAPER PRODUCTION.

Application filed August 23, 1923. Serial No. 659,013.

This invention relates to improvements in refining engines for paper production, and particularly to that type of machine employed in performing the final refining operations upon pulp to be used in the manufacture of paper board or sheet.

The primary object of the invention is to provide a machine of a greater capacity than machines heretofore manufactured, 10 and one which will perform its refining operations with substantially the same degree of perfection when either small quantities of pulp are being fed through the machine or when large quantities are being 15 fed through, the machine being provided with automatic means for accommodating widely varying quantities of pulp. The accomplishment of the foregoing feature of the invention makes possible the direct connection of my refining engine with any ordinary type of beating engine, whereby the pulp flows directly from the beating engine to the refining engine without the intervention of the usual feed regulating devices.

20 Another object of the invention is to provide a refining engine in which the cutting roll is floated so that it may assume different positions with respect to the stationary cutting blades dependent upon the quantity or character of the pulp passing between the blades of the cutting roll and the stationary blades. This construction results in great economy of operation because in the event foreign uncuttable matter enters the 30 refiner, the cutter wheels will be raised so as to allow the foreign substance to pass through without damage either to the stationary blades or to the blades of the cutter wheel.

35 Another object of my invention is to provide readily adjustable means for altering the effective weights of the cutter wheels so as to readily change the character of the pulp refinement.

40 Another object of the invention is to so associate two or more refining engines that they may be readily operated either in series or in parallel, or may be operated as separate units in the event that different 45 characters of pulp are desired.

Still further objects of the invention will appear from an examination of the drawings and from the following specification and claims.

50 My invention is illustrated in the accompanying drawings, in which—

Figure 1 is an elevation of the preferred form of my invention showing the fluid pressure connections by means of which the cutter rolls are raised and lowered, and by 60 means of which the pressure under which they operate is controlled;

Figure 2 is a plan view of the preferred form of my invention, the right hand portion being in section;

Figure 3 is a vertical section through the refining machine proper showing a method of connecting the same with a beating engine;

Figure 4 is a plan view of a modification 70 in which the cutter rolls are raised and lowered by means of hand operated screws, and

Figure 5 is an elevation of the modification shown in Figure 4.

The structure of my invention comprises primarily a bin or trough 10 having compartments 11 at the ends thereof for reception of pulp emulsion from any desired form of beating engine 12. The top of this bin is closed by a removable cover or deck 13. The beating engine partially illustrated in Figure 3 is that shown and described in my patent application, Serial Number 596-272, filed October 23, 1922. Next adjacent the compartments 11 are compartments forming the housings for the cutter wheels 14. The bases of these housings are in the form of slightly less than half cylinders, and are lined with blades 15 mounted 80 in four groups, the blades of each group being held in frames 16 wherein they are bound by wooden wedges 17 so that the frames 16 with their wedges and blades can 85 be removed as units.

The cutter wheels 14 are similarly provided with blades 18 extending lengthwise of the cylindrical surface of the wheel, these blades being similarly secured in place by wedge-shaped blocks of wood 19, the blades 90 of the bed and those of the wheel being preferably set somewhat diagonally so that they will have a shearing action against one another. The blades of the wheel are also 95 preferably made of broader material than the blades of the bed, which construction has been found in practice to assist in maintaining the sharpness of the edges of the blades.

The shafts 21 which carry the cutter rolls 14 and the belt or pulley wheels 22 are supported in bearings 23 outside the bin, these 110

bearings being mounted upon yokes 24, the ends of which are supported upon four pistons 25 mounted within the cylinders 26. In order to seal the openings through which the shafts 21 extend in the walls of the bin 10, I provide a collar 27 for each opening, each collar having a flange 28 fitted within a channel boss 29 in such manner as to permit the shaft with its collar to move vertically with respect to the wall of the bin without undue leakage of the pulp and fluid.

The central portion of the bin 10 is provided with two discharge openings 31 and 32. A partition 33 divides the chamber 30 into two parts, one associated with each of the cutter wheels 14. A valve mechanism 34, corresponding to that shown and described in my application, Serial No. 623,694, filed March 8, 1923, is arranged for opening and closing a port 35 within this partition 33.

Within the central chamber 30 are two adjustable weirs 36 provided with operating handles 37 which are extended outside the side walls of the bin and which are arranged to be locked in any one of a plurality of rotary positions.

The spaces within the cylinders 26 and below the pistons 25 of the four cylinders which control one cutting wheel are connected by a pipe line 40, a valve 41 and pipe line 42 with a tank 43 containing oil or other suitable fluid under high pressure. The pipe line 40 is provided with an expansion chamber 44 and with a pressure gauge 45. The spaces above these pistons 25 are likewise connected in groups of four by means of pipe line 46, valve 47 and pipe line 42 with the said high pressure chamber 43. Pipe line 46 is also provided with an expansion chamber 48 and with a pressure gauge 49. The valves 41 and 47 are three port valves connected with a pipe line 50 to a reservoir 51 from which the oil or other fluid may be pumped back into the high pressure tank 43 by means of the gear pump 52.

In the modification shown in Figures 4 and 5, the cutter rolls are raised and lowered by means of screws 55 about which sleeves 56 are threaded. Surrounding each of these sleeves is a pair of springs 57, 58, the spring 57 abutting the lower side of the yoke end 59 and the spring 58 abutting the upper side thereof, so that by the vertical adjustment of the sleeve 56 by means of the screw 55, the yoke can be raised or lowered, or caused to press downwardly with any desired degree of pressure.

Four screws 55 controlling one cutter roll are pressurably adjusted in unison by means of the worm and worm wheel 60 and 61 and by the chains 62 and sprockets 63.

When the two refining rolls forming the

right and left hand parts of my refining engine are operated in series, the pulp from the beating engine is fed into the right hand receiving chamber 11 through the valve 70, whence it passes between the blades 18 of 70 the right hand cutter wheel 14 and the stationary blades 16, the cutter wheel 14 at this time being rotated in a clockwise direction as viewed in Figure 3. A certain portion of the pulp emulsion will be carried around the top of the cutter roll and will again pass between the blades, the proportions being regulated by the adjustable weir 36. The refined pulp is delivered into the central chamber 30, passes through the 80 port 35 in the partition 33, and then passes between the blades of the cutter wheel and bed at the left of the engine, being delivered into the left hand chamber 10 from which it flows through the discharge passage 71, 85 the adjustable weir 72 being used in this instance to regulate the proportions of the pulp emulsion which pass around the second cutter wheel.

Where the cutter wheels are operated in 90 parallel, the pulp is fed into both of the chambers 11 of the refining engine, and is delivered into the central chamber 30 from which it is drawn through one or both of the discharge ports 31, 32, the port 35 being left open where the rolls are adjusted for similar refinement and being closed where the rolls are adjusted for different refinement. The adjustable weir 72 is opened when the left hand half of my refining engine is operated in parallel with the right hand half.

In order to secure the desired degree of refinement of the pulp, the valves 41 and 47 are opened and closed until fluid pressures have been obtained above and below the pistons 25 which gives a desired pressure between the movable and stationary blades. When the quantity of pulp increases through increased delivery from the beating 110 engine, the fluid in the upper sections of the cylinders will be forced into the expansion chamber 48, while the fluid from the expansion chamber 44 will flow into the cylinders below the pistons 25, thus permitting the roll to assume a position somewhat removed from the stationary blades but having a pressure toward the stationary blades which is somewhat greater than that which it had when the roll was 120 closer to the blades.

In the operation of the structure shown in Figures 4 and 5, the initial pressure between the movable and stationary blades is obtained by rotation of the screws to bring about any desired preliminary pressure. This construction is less flexible than that shown in Figures 1 to 3 because of the greater difficulty in regulating the relative pressures of the lower and upper springs. 120

With the proper adjustment of parts, however, the device of this modification may be operated in the same manner as the fluid controlled device of the preferred form shown in Figures 1 to 3.

Although I have shown and described my invention with respect to certain details of construction, it is to be understood that I do not wish to be unduly limited thereto, certain modifications being possible without departing from the spirit or scope of my invention.

Having thus described my invention, what I claim is:

1. A machine for refining paper pulp comprising one or more rolls carrying cutter blades, stationary cutter blades beneath said rolls and occupying a section less than one-half of a cylinder, fluid means for yieldingly supporting said axles whereby the rolls will assume different positions with respect to the stationary blades depending upon the quantity of pulp passing between the blades on the roll and the stationary blades, and means for adjusting the pressures above and below said yielding supporting means for the rolls.

2. A pulp refining engine for use in the manufacture of paper, comprising a cylindrical cutter roll having blades mounted thereon, a bed having arcuately arranged blades mounted therein, journals for said roll, fluid means for yieldingly floating said journals to support said roll, and means for controlling the pressure of said fluid means on said journals.

3. In a refining engine for the preparation of pulp for the manufacture of paper, the combination with a cutter roll, of stationary blades beneath the cutter roll, a journal for the cutter roll, a cylinder, a piston within the cylinder supporting said journal, a source of fluid under pressure, means for conducting the fluid under pressure into said cylinder above and below said piston, and means for regulating the degrees of pressure of the fluid in said cylinder above and below said piston.

4. In a refining engine for paper pulp, the combination with a cutter roll, of a journal therefor, a piston supporting said journal, a cylinder within which said piston operates, a source of fluid under pressure, a pressure gauge connected with the cylinder, a valve for regulating the quantity of fluid in said cylinder and the pressure of said fluid as indicated on said gauge, and an expansion chamber in communication with

said cylinder having a gaseous fluid therein to permit small quantities of fluid to pass to and from said cylinder during slight motion of the piston in said cylinder whereby the said cutter roll may move away from the stationary blades when the quantity of material passing between the cutter roll and the stationary blades exceeds a predetermined minimum.

5. In a refining engine for paper pulp, the combination with rotating and stationary blades responsive to variations in the quantity of paper pulp passing between them, and a beating engine directly connected to discharge into said refining engine, the natural fluctuations in the discharge from the beating engine being compensated for by the movement of the cutter roll in the refining engine.

6. In a refining engine for paper pulp, the combination with a bin, of a pair of cutter rolls in said bin, a chamber at each end of the bin, a divided chamber at the middle of the bin between the rolls, and means to close and open a port in the partition dividing said middle chamber whereby pulp may be fed either from the two end chambers to the middle chamber by operating the rolls in parallel or may be fed serially from one end chamber through the middle chamber to the other end chamber by operating the rolls in series.

7. A pulp refining engine for use in the manufacture of paper, comprising a cylindrical cutter roll having blades mounted thereon, a bed having blades therein mounted for co-operation with the blades of said roll, journals for said roll, a hydraulic jack for supporting said journals, and a gas containing expansion chamber communicating with the liquid of said hydraulic jack whereby said journals are yieldably supported.

8. A refining engine for paper pulp comprising a roll having blades thereon, a bed having blades therein for co-operating with said roll, a beam at each end of said roll extending transversely to the axis thereof, a journal for said roll supported by each of said beams, pistons connected with each end of said beams, a cylinder for reciprocably mounting each of said pistons, and means for supplying fluid under pressure to said cylinders to adjustably support said roll relatively to said bed.

In witness whereof, I hereunto subscribe my name this 8 day of August, 1923.

JAMES T. MURPHY.
